(57) **CLAIM**

The ornamental design for an extrusion, as shown and described.

DESCRIPTION

FIG. 1 is a perspective view of an extrusion in accordance with my new design;

FIG. 2 is a top plan view thereof;

FIG. 3 is a bottom plan view thereof;

FIG. 4 is a left side elevation view thereof;

FIG. 5 is a right side elevation view thereof; and,

FIG. 6 is an enlarged front elevation view thereof, the rear elevation view being a mirror image thereof.

The extrusion is shown with a symbolic break in its length. The appearance of any portion of the extrusion between the jagged break lines forms no part of the claimed design.
